(57) **CLAIM**

The ornamental design for an earring, as shown and described.

DESCRIPTION

FIG. 1 is a top view of a first embodiment of the earring;
FIG. 2 is a bottom view of the earring illustrated in FIG. 1;

FIG. 3 is a right elevational view of the earring illustrated in FIG. 1;

FIG. 4 is a left elevational view of the earring illustrated in FIG. 1;

FIG. 5 is a front view of the earring illustrated in FIG. 1;

FIG. 6 is a rear view of the earring illustrated in FIG. 1;

FIG. 7 is a perspective view of the earring illustrated in FIG. 1

FIG. 8 is a top view of a second embodiment of the earring;
FIG. 9 is a bottom view of the earring illustrated in FIG. 8;

FIG. 10 is a right elevational view of the earring illustrated in FIG. 8;

FIG. 11 is a left elevational view of the earring illustrated in FIG. 8;

FIG. 12 is a front view of the earring illustrated in FIG. 8;
FIG. 13 is a rear view of the earring illustrated in FIG. 8;

FIG. 14 is a perspective view of the earring illustrated in FIG. 8

FIG. 15 is a top view of a third embodiment of the earring;
FIG. 16 is a bottom view of the earring illustrated in FIG. 15;

FIG. 17 is a right elevational view of the earring illustrated in FIG. 15;

FIG. 18 is a left elevational view of the earring illustrated in FIG. 15;

FIG. 19 is a front view of the earring illustrated in FIG. 15;

FIG. 20 is a rear view of the earring illustrated in FIG. 15;

FIG. 21 is a perspective view of the earring illustrated in FIG. 15;

FIG. 22 is a top view of a fourth embodiment of the earring;
FIG. 23 is a bottom view of the earring illustrated in FIG. 22;

FIG. 24 is a right elevational view of the earring illustrated in FIG. 22;

FIG. 25 is a left elevational view of the earring illustrated in FIG. 22;

FIG. 26 is a front view of the earring illustrated in FIG. 22;

FIG. 27 is a rear view of the earring illustrated in FIG. 22; and,

FIG. 28 is a perspective view of the earring illustrated in FIG. 22.
